UNITED STATES PATENT OFFICE

137,733

DESIGN FOR A KITCHEN RANGE

Charles J. Rogers, River Forest, Ill., assignor to Crown Stove Works, Chicago, Ill., a corporation of Illinois

Application February 2, 1944, Serial No. 112,408

Term of patent 14 years

(Cl. D81—4)

To all whom it may concern:

Be it known that I, Charles J. Rogers, a citizen of the United States, residing at River Forest, in the county of Cook and State of Illinois, have invented a new, original, and ornamental Design for a Kitchen Range, of which the following is a specification, reference being had to the accompany drawing, forming part thereof.

The figure is a perspective view of a kitchen
range embodying my new design both sides
thereof being identical.

I claim:

The ornamental design for a kitchen range,
substantially as shown and described.

CHARLES J. ROGERS.
